His ATTORNEY.

UNITED STATES PATENT OFFICE.

FRANK H. LONGACRE, OF KANSAS CITY, MISSOURI.

DESIGN FOR A HEAT GUARD STOVE PLATE.

Application filed August 24, 1922. Serial No. 3,544. Term of patent 3½ years.

To all whom it may concern:

Be it known that I, FRANK H. LONGACRE, a citizen of the United States, residing at Kansas City, in the county of Jackson and State of Missouri, have invented a new, original, and ornamental Design for a Heat Guard Stove Plate, of which the following is a specification, reference being had to

the accompanying drawing, forming part thereof.

The figure is a perspective view of a heat guard stove plate, showing my new design.

I claim:—

The ornamental design for a heat guard stove plate, as shown.

FRANK H. LONGACRE.
